UNITED STATES PATENT OFFICE.

CATHERINE R. MACK, OF LOS ANGELES, CALIFORNIA.

BED AND DOUCHE PAN.

Application filed July 5, 1922. Serial No. 572,972.

To all whom it may concern:

Be it known that I, CATHERINE R. MACK, a citizen of the United States, residing at Los Angeles, in the county of Los Angeles and State of California, have invented new and useful Improvements in Bed and Douche Pans, of which the following is a specification.

This invention relates to bed and douche pans and has for its object to provide a pan that will not readily tip over and which is provided with an inclined bottom from the top of the rear end forwardly. An object is to provide a draining bed pan.

Other objects will be made manifest in the following specification of an embodiment of the invention illustrated in the accompanying drawings, in which—

Figure 1 is a perspective of the pan and draining attachment.

Fig. 2 is a plan of the pan.

Fig. 3 is a longitudinal section.

Fig. 4 is a rear end elevation.

The pan has a surrounding flange or base 2 of substantially uniform height to provide a stable base. The rear end is semicircular and has an inwardly turned rim 3 of horseshoe form, the ends of which approach a drain wall 4.

The pan has a bottom 5 inclining from the rear end down to the bottom of the front wall 4, and this has a drain nipple 6 leading from the pan. The nipple has a removable cap 7 so that a noncollapsible drain hose 8 may be applied to the nipple. The hose leads to a suitable receptacle 9.

The rim has an inlet opening 3^a.

Further embodiments, modifications and changes may be resorted to within the spirit of the invention as here claimed.

What is claimed is:

1. A douche having an upstanding wall-forming flange with an inturned rim forming the seat part of the douche, and a bottom inclining from the upper rear part of the flange down to the opposite end.

2. A douche having a horseshoe-shaped rim and a supporting flange along the perimeter thereof, said flange extending transversely between the spaced ends of the rim, and a bottom secured to the flange, said bottom inclining down from the upper part of the curved end of the flange to the bottom of the transverse part of the flange.

In testimony whereof I have signed my name to this specification.

CATHERINE R. MACK.
